(57) **CLAIM**

The ornamental design for a ceiling panel system, as shown and described.

DESCRIPTION

This application claims the benefit of priority of U.S. Provisional Patent Application No. 63/025,050, filed May 14, 2020, which is hereby incorporated herein by reference in its entirety.

FIG. 1 is a top perspective view of a ceiling panel system; FIG. 2 is a bottom perspective view thereof;

FIG. 3 is a top view thereof;

FIG. 4 is a bottom view thereof;

FIG. 5 is a front elevation view thereof;

FIG. 6 is a rear elevation view thereof;

FIG. 7 is a right side elevation view thereof; and,

FIG. 8 is a left side elevation view thereof.

The broken lines depict portions of the ceiling panel system that form no part of the claimed design.

1 Claim, 6 Drawing Sheets
